LOOP-TAKER AND FEED-ACTUATING MECHANISM FOR SEWING MACHINES

Frank Parry, Bridgeport, Conn., assignor to The Singer Manufacturing Company, Elizabeth, N. J., a corporation of New Jersey

Application April 11, 1942, Serial No. 438,516

11 Claims. (Cl. 112—215)

This invention relates to sewing machines and has for an object to provide a sewing machine with loop-taker and feed-actuating mechanisms capable of operation at high speeds with a minimum of vibration of the sewing machine.

Another object of this invention is to provide improved loop-taker and feed-actuating mechanisms adapted for sewing machines having a work-supporting arm of the cylindrical bed type, and in which the work is fed crosswise of the work-supporting arm. Other and more specific objects of the invention will be apparent from the following description and claims.

The invention comprises the devices, combinations and arrangements of parts hereinafter described in connection with the accompanying drawings, which illustrate a preferred embodiment of the invention and in which:

Fig. 1 is a front elevation, partly in vertical section, of a sewing machine containing the present improvement. Fig. 2 is an enlarged front end elevation of the work-arm of the machine, with the end-cap of the work-arm shown in section. Fig. 3 is an enlarged vertical section longitudinally of the free end portion of the work-arm; the section being taken in substantially the vertical plane containing the axis of rotation of the loop-taker shaft. Fig. 4 represents an enlarged cross-section through the bracket-arm standard of the machine, the section being taken on substantially the line 4—4 of Fig. 1. Fig. 5 represents an enlarged cross-section of the work-arm on substantially the line 5—5 of Fig. 1. Fig. 6 represents a transverse section of the work-arm on substantially the line 6—6 of Fig. 3, and illustrates the feed-advance rocker. Fig. 7 represents a transverse section of the work-arm on substantially the line 7—7 of Fig. 3, and shows the feed-bar in elevation. Fig. 8 is a top-plan of the work-arm broken away from its supporting base; the throat-plate and cover-plates being removed from the work-arm and the work-arm end-cap being shown in section.

As illustrated in the drawings, the sewing machine has a hollow supporting base 10, from which extends a horizontally disposed work-supporting arm 11 of the cylinder-bed type having a free outer end; said work-supporting arm being preferably integral with the base 10. Rising from the base 10 is the hollow standard 12 of a bracket-arm 13 which terminates at its free end in a head 14 overhanging the free end of the work-arm 11.

Rotatably journaled in the bracket-arm 13 is a horizontally disposed rotary actuating or main

shaft 15 suitably connected to impart endwise reciprocatory movements to a vertically disposed needle-bar 16 carrying at its lower end an eye-pointed needle 17. Also supported by the bracket-arm head 14 for endwise movement is the usual vertically disposed and spring-depressed presser-bar 18 carrying at its lower end a presser-foot 19.

Complemental to the needle 17, in the formation of lock-stitches, is a rotary loop-taker 20 of the horizontal-axis rotary hook type disposed within the work-arm 11 at the free end thereof. The loop-taker 20 has a cylindrical side wall 21 and an end wall 22 from which extends a reduced hub 23 having a shaft-aperture 24 closed at the inner side of the end wall 22 by a disk 25 set into the end wall 22. The side wall 21 of the loop-taker is partly cut away to provide a needle-thread loop seizing beak 26; said side wall 21 being also internally grooved circumferentially to provide a raceway 27. Journaled in the raceway 27 is the peripheral bearing-rib 28 of a thread-carrier 29. The thread-carrier 29 houses the usual thread-case 30 which contains a mass of under thread about which the needle-thread loops are cast by the loop-taker. The thread-carrier 29 is restrained against rotation with the loop-taker and to that end the thread-carrier is provided with the usual stop-notch 31 entered by a stationary stop-lug 32. The stop-lug 32 extends from an angular stop-member 33 secured by screws 34 against the end face of the work-arm 11. The hub-aperture 24 has the usual lubricant-conducting connections with the raceway 27; said connections comprising a radial duct 35 formed in the end wall 22 of the loop-taker and open to an axially extending duct 36 in the loop-taker side wall 21.

The hub 23 of the loop-taker is secured by screws, as 37, upon the reduced end of a horizontally disposed loop-taker shaft 38 extending lengthwise of the work-arm 11. The end of the shaft 38 is preferably spaced from the disk 25 of the loop-taker end wall, thereby to provide the loop-taker with a lubricant-collecting cavity beyond the end of the shaft and open to the radial duct 35 which is connected with the loop-taker raceway.

As illustrated more particularly in Fig. 3 of the drawings, the loop-taker shaft 38 is rotatably journaled in a needle-roller bearing 39 disposed directly adjacent the hub 23 of the loop-taker, whereby the shaft 38 is adequately supported close to the loop-taker. The roller-bearing 39 is disposed within and carried by a bushing 40 having

the longitudinal shaft-opening 40' thereof slightly larger, diametrically, than the shaft 38, whereby the inner face of the bushing is spaced slightly from the shaft. The bushing 40 is suitably secured in a horizontal hole 41 formed in a transverse wall 42 of the work-arm 11 near the free end thereof.

At its opposite end, the loop-taker shaft 38 is journaled in a ball-bearing 43 supported by a lug 44 depending from the upper wall of the base 10. Carried by the shaft 38 within the base 10 is a belt-pulley 45 connected by a clip-belt 46, extending through the arm-standard 12, to a belt-pulley 47 carried by the main or bracket-arm shaft 15. The pulleys 45 and 47 are proportioned so that the loop-taker shaft 38 rotates twice for each rotation of the main shaft 15, and the loop-taker shaft 38 is located in the work-arm so that the axes of rotation of the shafts 15 and 38 are disposed in a common vertical plane. Between its ends, the loop-taker shaft 38 passes freely through a bushing 48 secured by a screw 49 in another transverse wall 50 of the work-arm; said wall 50 being located at the juncture of the base 10 and work-arm 11. A collar 51 is secured upon the shaft 38 to engage one end of the bushing, thereby to restrain said shaft against endwise movement in one direction.

The work is advanced across the work-arm 11 by a drop-feed feed-dog 52, operating through a suitably slotted and flattened portion of a throat-plate 53 having a needle-aperture 54; said throat-plate having segmental wings secured by screws 55 upon the curved front and rear walls of the work-arm. The feed-dog 52 overhangs the loop-taker 20 and is secured by screws 56 upon the upper end of an upright feed-bar 57 having a clearance opening 58 for the end portion of the bushing 40 which supports the roller-bearing 39; said feed-bar 57 being disposed directly adjacent to the loop-taker hub 23 and at the side of the loop-taker opposite the free end of the work-arm.

The lower end of the feed-bar 57 has a horizontally apertured split sleeve 59 extending under the loop-taker 20 and clamped by a screw 60 upon a fulcrum-pin 61 which lengthwise extends parallel to the loop-taker shaft 38 and is disposed vertically below said shaft. The opposite ends of the fulcrum-pin 61 are pivotally journaled in a feed-lift rocker comprising horizontally spaced rocker-arms 62 and 63; said rocker-arms extending horizontally forwardly from and being carried by one end of a feed-lift rock-shaft 64 disposed substantially parallel to the loop-taker shaft 38 and rearward of the vertical plane containing the axis of rotation of said shaft 38.

The feed-lift rock-shaft 64 is journaled in a bearing-bushing 65 suitably secured in an aperture in the transverse wall 42 of the work-arm 11. Adjacent its opposite end, the rock-shaft 64 is journaled in a bearing-bushing 66 carried by the transverse wall 50. Clamped upon the end of the rock-shaft 64, within the base 10, is the split hub of a depending crank-arm 67. The crank-arm 67 is pivotally connected, in any suitable manner, to one end of a pitman 68 having a strap embracing a feed-lift eccentric 69 carried by a primary feed-actuating shaft 70; the pitman 68 extending rearwardly and upwardly from said shaft. While the pitman-strap may directly embrace the eccentric 69, it is preferred to interpose therebetween a needle-roller bearing 71, in the manner as illustrated

more fully in the U. S. patent to S. Zonis, No. 2,267,581, dated December 23, 1941.

The feed-actuating shaft 70 is lengthwise parallel to the main shaft 15; one end of said shaft 70 being rotatably journaled in a bearing-bushing 72 suitably secured in the lower portion of the work-arm transverse wall 56. The opposite end of the shaft 70 is journaled in a ball-bearing 73 supported in a wall 74 connecting the front and rear walls of the base 10. Adjacent the ball-bearing 73, the rotary shaft 70 carries a belt-pulley 75 connected by a clip-belt 76 to a pulley 77 carried by the main-shaft 15; said belt 76 extending through the bracket-arm standard 12, and said pulleys 75 and 77 being proportioned so that the shafts 15 and 70 rotate in one-to-one relation. The feed-actuating shaft 70 is disposed vertically below the loop-taker shaft 38; the axes of rotation of the main-shaft 15, loop-taker shaft 38 and feed-actuating shaft 70 being all disposed in a common vertical plane.

The feed-actuating shaft 70 also carries a feed-advance eccentric 78 which is adjustable as to eccentricity and is constructed substantially in accordance with the feed-advance eccentric disclosed in the U. S. patent to W. Myers, No. 2,128,031, dated August 23, 1938. In the present instance, as illustrated in Fig. 4 of the drawings, the means employed for manually locking the adjusting member of the feed-advance eccentric 78 while effecting adjustment of said eccentric comprises a spring-retracted plunger-rod 79 supported by the front wall of the base 10 for endwise movement.

The feed-advance eccentric 78 is embraced by the strap of a pitman 80 extending forwardly in an upwardly inclined direction, from the feed-actuating shaft 70. Preferably, a needle-roller bearing 80' is interposed between the pitman-strap and the eccentric as disclosed in the above mentioned Patent No. 2,267,581. The pitman 80 is pivotally connected, in a suitable manner, to a crank-arm 81 having a split hub clamped upon one end of a feed-advance rock-shaft 82 disposed vertically below and parallel to the loop-taker shaft 38 so that its rocking axis is also contained in the vertical plane containing the rotation axes of the shafts 15, 38 and 70. This arrangement of the several shafts referred to lends itself to high speed operation of the machine, as vibration is thereby reduced to a minimum.

Adjacent the crank-arm 81, the feed-advance rock-shaft 82, is journaled in a bearing-bushing 83 secured in the transverse wall 50 of the work-arm 11. Adjacent its opposite end, the rock-shaft 82 is journaled in a bushing 84 suitably secured in the work-arm wall 42. Beyond the wall 42, the end of the rock-shaft 82 carries an upright feed-advance rocker 85 disposed closely adjacent to the feed-bar 57 and at the side of said feed-bar opposite the loop-taker side thereof. The feed-advance rocked 85 is formed with an opening 86 therein, affording clearance for the loop-taker shaft supporting bushing 40. At its upper end, above the bushing 40, the feed-advance rocker 85 is forked to provide an upwardly open rectangular guideway 87 in which is slidably disposed a pivot-block 88. The pivot-block 88 is apertured to receive a pivot-pin 89 extending horizontally from the feed-bar 57. The forward and return movements thus imparted to the feed-bar 57 by the feed-advance rocker 85 are coordinated with the rising and falling move-

ments imparted to said feed-bar by the feed-lift rocker 62, 63 to transmit operative work-advancing movements to the feed-dog 52.

The described compactly arranged feeding mechanism lends itself to location of the feed-dog 52 close to the free end of the work-arm 11 without interfering with removal from the loop-taker 20 of the thread-case 30 for thread replenishment purposes. The feed-dog 52 is nevertheless, adequately supported at the front and rear sides of the loop-taker shaft 38 and is actuated to minimize tilting of the feed-dog with respect to the flattened upper face of the throat-plate 53.

A segmental end-cap 90 is removably applied to the work-arm 11 to enclose the lower and front end portions thereof; the end wall of said end-cap having an opening 91 to provide for removal of the thread-case 30 without requiring removal of the end-cap. The base 10 of the machine is preferably supported by a sub-base 92 of any suitable height.

As illustrated in Fig. 5 of the drawings, the transverse wall 42 of the work-arm is provided at the rearward side thereof with an upwardly open and forwardly inclined lubricant-pocket or primary reservoir 93; the open or upper end of the reservoir 93 being disposed below and spaced from the flattened portion of a cover-plate 94 removably secured by screws 95 upon the work-arm wall 42. Between the cover-plate 94 and the throat-plate 53, another and similarly shaped cover-plate 96 is detachably secured by screws 97 upon the work-arm 11 to provide for access to the feed-mechanism disposed below said cover-plate 96. Lubricant may be supplied to the reservoir 93 through an aperture 98 provided in the cover-plate 94.

Disposed in the reservoir 93 and extending from the open upper end thereof to terminate in a cavity 99 in the upper face of the work-arm wall 42 is a lubricant-conducting wick 100. Adapted to engage the end of the wick 100 in the wall-cavity 99 is one limb of a bent connection-wick 101, of which the other limb extends downwardly through a pivot-sleeve 102 free for turning movement in a vertical aperture formed in the wall 42. The pivot-sleeve 102 is provided with a short crank-arm 104 extending horizontally beyond the edge of the cover-plate 94, whereby the pivot-sleeve 102 may be manually turned at will to shift the connection-wick 101 into and out of engagement with the wick 100; it being understood that the connection-wick 101 is packed into the pivot-sleeve 102 for turning movement therewith. The lower end of the connection-wick 101 extends downwardly from the pivot-sleeve 102 through a radial aperture 105 in the bushing 40, thereby to deliver lubricant into the shaft-opening 40' of the bushing 40.

Within the bushing 40, the loop-taker shaft 38 is externally provided with a spiral lubricant-impelling thread 106 disposed directly below the bushing aperture 105 and leading to a radial aperture 107 in the shaft 38. The shaft 38 is additionally provided with an oppositely spiralling lubricant-impelling thread 108 at the opposite side of and also leading to the shaft-aperture 107. The shaft-aperture 107 opens into a longitudinal bore 109 of the shaft 38; said bore being open at 70 the end of the shaft within the hub 23 of the loop-taker.

The wick 100 serves to feed lubricant from the reservoir 93 to the connection-wick 101 when said wicks are in contact with each other. The 75

wick 101 feeds the lubricant into the bushing 40, and the spiral thread 106 impels the lubricant, thus supplied thereto, lengthwise of the shaft 38 to the shaft-aperture 107. The counter-spiraling thread 108 guards against escape of excess lubricant from the end of the bushing 40 adjacent the loop-taker, while permitting a modicum of the lubricant to find its way to the needle-roller bearing 39. The lubricant thus supplied to 10 the hub-cavity 24 is delivered to the raceway 27 of the loop-taker in the usual manner.

The work-arm wall 42 is provided with a lubricant-duct 110 connecting the reservoir 93 with the bushing-hole 41 of said wall; the bushing 40 having a circumferential groove 111 located to receive lubricant discharged from the duct 110. Another duct 112 in alignment with the duct 110, is provided in the wall 42 and connects the bushing-hole 41 with a supplemental lubricant-reservoir 113 comprising an upwardly open and substantially vertical pocket formed in the wall 42 below the cover-plate 94.

Extending from and through a side wall aperture of the supplemental reservoir 113 is a lubricant-conducting wick 114 having the opposite end thereof entering a radial aperture 115 of the feed-lift rock-shaft 64 beyond the end of the bushing 65. The radial shaft-aperture 115 opens into a longitudinal bore of the shaft 64, through which shaft-bore lubricant is supplied to additional radial ducts 116 of the shaft 64 within said bushing 65. Another wick 117 extends from the supplemental reservoir 113, through a side wall aperture of said reservoir and into the open end of a longitudinal bore 118 of the feed-advance rock-shaft 82; said bore 118 being connected by suitable radial shaft-apertures 119 with the bearing-face of the bushing 84 in which one end portion of the shaft 82 is journaled.

The supplemental reservoir 113 has a third side wall aperture into which extends one end of a tubular lubricant-conduit 120 lengthwise inclined downwardly from said reservoir. The opposite end of the conduit 120 overhangs a catch-basin at one end of a short tube 121 supported in an aperture of the work-arm wall 50 to extend horizontally from said wall. An aperture of the tube 121 is connected by suitable ducts, provided in the wall 50 and in the bushing 72, with the bearing aperture 72' of said bushing 72; said bearing aperture 72' being closed at the work-arm side of the bushing 72 by a suitable plug 122 spaced slightly from the end of the shaft 70. The shaft 70 is provided with a longitudinal bore 123 and with suitable radial apertures connecting said bore with the needle-bearings 71, 80' for the pitman straps embracing the feed-lift eccentric 69 and the feed-advance eccentric 78.

From the foregoing description, it will be understood that when lubricant is supplied through the aperture 98 of the work-arm cover-plate 94 to the primary lubricant-reservoir 93, the lubricant rising in the reservoir 93 will flow through the duct 110 the circumferential bushing-groove 111 and then through the duct 112 into the supplemental reservoir 113. As the lubricant rises in the reservoir 113, it flows through the conduit 120 to the lubricant-conducting connections with the bore 123 of the feed-actuating shaft for delivery to the needle-roller bearings 71 and 80'.

The base 10 is internally provided with an oil-

well 124, from which oil is fed by wicks 125 and 126 into longitudinal bores of the feed rock-shafts 64 and 82 for delivery through suitable radial apertures in said rock-shafts to the bearings thereof. The remaining bearings of the loop-taker and feed mechanisms may be lubricated in any suitable manner.

Having thus set forth the nature of the invention what I claim herein is:

1. In a sewing machine having a frame including a work-support and a bracket-arm overhanging said work-support, in combination, a rotary arm-shaft journaled in said bracket-arm, a loop-taker shaft rotatably journaled below said work-support, driving connections with said arm-shaft for rotating said loop-taker shaft a plurality of times for each rotation of said arm-shaft, a feed-actuating shaft journaled below and in spaced relation to said loop-taker shaft, driving connections with said arm-shaft independent of the loop-taker shaft driving connections therewith for rotating said feed-actuating shaft once for each rotation of the arm-shaft, said arm-shaft, loop-taker shaft and feed-actuating shaft having substantially parallel rotation axes disposed in substantially the same plane, a work-advancing feed-dog operating through said work-support, and connections with said feed-actuating shaft for imparting operative work-advancing movements to said feed-dog.

2. In a sewing machine having a frame including a work-support, in combination, substantially parallel loop-taker and feed-actuating shafts rotatably journaled below said work-support, a feed-advance rock-shaft journaled below said work-support and having its longitudinal axis in substantially a vertical plane containing the axes of rotation of said loop-taker and feed-actuating shafts, means for rotating said loop-taker and feed-actuating shafts, means for actuating said rock-shaft from said feed-actuating shaft, a work-advancing feed-dog operating through said work-support, operative connections with said rock-shaft for imparting work-advancing and return movements to said feed-dog, and means for imparting rising and falling movements to said feed-dog.

3. In a sewing machine having a frame including a work-support, in combination, a loop-taker shaft rotatably journaled below said work-support, a feed-actuating shaft rotatably journaled vertically below and in spaced relation to said loop-taker shaft, driving connections for rotating said loop-taker shaft a plurality of times for each rotation of said feed-actuating shaft, a feed-advancing rock-shaft disposed between and substantially parallel to said loop-taker and feed-actuating shafts, said three shafts having their longitudinal axes disposed in substantially the same vertical plane, means for actuating said rock-shaft from said feed-actuating shaft, a feed-lift rock-shaft disposed below said work-support and substantially parallel to said feed-advance rock-shaft, means for actuating said feed-lift rock-shaft from said feed-actuating shaft, a feed-dog operating through said work-support, and connections with said rock-shafts for imparting operative work-advancing movements to said feed-dog.

4. In a sewing machine having a frame including a work-support and a bracket-arm overhanging said work-support, in combination, a rotary arm-shaft journaled in said bracket-arm, substantially parallel loop-taker and feed-actuating shafts rotatably journaled below said work-sup-

port, a feed rock-shaft journaled below said work-support and disposed substantially parallel to said arm-shaft, said four shafts having their longitudinal axes in substantially a common vertical plane, driving connections for rotating said loop-taker shaft in two-to-one and said feed-actuating shaft in one-to-one relation to said arm-shaft, means for actuating said rock-shaft from said feed-actuating shaft, a work-advancing feed-dog, and means including operative connections with said rock-shaft for actuating said feed-dog from said feed-actuating shaft.

5. In a sewing machine having a frame including a work-support and a bracket-arm overhanging said work-support, in combination, a rotary-arm shaft journaled in said bracket-arm, a rotary loop-taker shaft journaled below said work-support, a rotary feed-actuating shaft journaled vertically below and in spaced relation to said loop-taker shaft, driving connections for rotating said loop-taker shaft in two-to-one and said feed-actuating shaft in one-to-one relation to said arm-shaft, a feed rock-shaft disposed between and substantially parallel to said rotary loop-taker and feed-actuating shafts, said four shafts having their longitudinal axes disposed in substantially the same vertical plane, means for actuating said rock-shaft from said feed-actuating shaft, a work-advancing feed-dog, and means including operative connections with said rock-shaft for actuating said feed-dog from said feed-actuating shaft.

6. In a sewing machine having a frame including a work-support, in combination, a loop-taker shaft rotatably journaled below said work-support, a rotary feed-actuating shaft journaled below and spaced vertically from said loop-taker shaft, driving connections for rotating said loop-taker shaft a plurality of times for each rotation of said feed-actuating shaft, a pair of feed rock-shafts disposed below said work-support and substantially parallel to said rotary feed-actuating shaft, one of said rock-shafts having its longitudinal axis in a vertical plane containing the axes of rotation of said loop-taker and feed-actuating shafts, connections with said feed-actuating shaft for actuating said rock-shafts, a work-advancing feed-dog, and operative connections with said rock-shafts for actuating said feed-dog.

7. In a sewing machine having a frame including a work-support and a bracket-arm overhanging said work-support, in combination, a rotary arm-shaft journaled in said bracket-arm, a rotary loop-taker shaft journaled below said work-support, a rotary feed-actuating shaft journaled vertically below and in spaced relation to said loop-taker shaft, said three rotary shafts having substantially parallel rotation axes disposed in a substantially common vertical plane, driving connections for rotating said shafts, a pair of substantially parallel feed rock-shafts journaled below said work-support, one of said rock-shafts having its longitudinal axis in substantially said plane, means for actuating said rock-shafts from said rotary feed-actuating shaft, a work-advancing feed-dog, and operative connections with said rock-shafts for actuating said feed-dog.

8. In a sewing machine having a frame including a hollow base and a work-arm of the free-end type extending from said base, in combination, a loop-taker shaft rotatably journaled in said work-arm and extending lengthwise of said work-arm into said base, a loop-taker carried by said shaft at the free end portion of

said work-arm, a feed-actuating shaft rotatably journaled in said base, driving connections for rotating said shafts, a feed rock-shaft journaled in and extending lengthwise of said work-arm into said base, said loop-taker shaft, feed-actuating shaft and rock-shaft having their longitudinal axes in substantially the same vertical plane, a crank-arm carried by said rock-shaft within said base, an eccentric carried by said feed-actuating shaft, a pitman connecting said eccentric and crank-arm, a second feed rock-shaft journaled in said work-arm at one side of said plane and lengthwise extending into said base, connections with said feed-actuating shaft for actuating said second rock-shaft, a work-advancing feed-dog disposed at the free end portion of said work-arm, and operative connections, with said rock-shafts for actuating said feed-dog.

9. In a sewing machine having a frame including a hollow base and a work-arm of the free-end type extending from said base, in combination, a loop-taker shaft rotatably journaled in and extending lengthwise of said work-arm into said base, a loop-taker carried by said shaft at the free end portion of said work-arm, a feed-actuating shaft rotatably journaled in said base, driving connections for rotating said loop-taker shaft a plurality of times for each rotation of said feed-actuating shaft, a feed-advance rock-shaft journaled in and extending lengthwise of said work-arm into said base, said three shafts having substantially parallel longitudinal axes disposed in substantially the same vertical plane, a feed-lift rock-shaft extending lengthwise of said work-arm into said base, divergent crank-arms carried by the respective feed rock-shafts, feed-advance and feed-lift eccentrics carried by said feed-actuating shaft within said base, pitmans connecting said eccentrics with said crank-arms, a work-advancing feed-dog disposed at the free end portion of said work-arm, and operative connections with said rock-shafts for actuating said feed-dog.

10. In a sewing machine, in combination, a horizontally disposed rotary loop-taker shaft, a loop-taker carried by one end of said shaft, a

5 feed-bar vertically disposed adjacent said loop-taker and having a loop-taker shaft clearance opening, a feed-dog extending laterally from said feed-bar and overhanging said loop-taker, a feed-lift rocker pivotally supporting said feed-bar for movement of said feed-bar about an axis substantially parallel to the axis of rotation of said loop-taker, means for actuating said feed-lift rocker, a feed-advance rocker disposed adjacent said feed-bar and having a loop-taker shaft clearance opening, said feed-advance rocker having its rocking axis substantially in a vertical plane containing the axis of rotation of said loop-taker shaft, means for actuating said feed-advance rocker, connections with said feed-advance rocker for rocking said feed-bar, and a bearing for said loop-taker shaft extending through said shaft clearance openings of said feed-bar and feed-advance rocker into close proximity to said loop-taker.

11. In a sewing machine, in combination a horizontally disposed rotary loop-taker shaft, a loop-taker carried by one end of said shaft, a tubular bearing-support, an antifriction bearing in said bearing-support for said loop-taker shaft, said antifriction bearing being disposed in close proximity to said loop-taker, a vertically disposed feed-bar embracing said antifriction bearing and having a clearance opening for said bearing-support, a feed-dog supported by said feed-bar and overhanging said rotary loop-taker, a pivotal support for said feed-bar below said loop-taker shaft and providing for movement of said feed-bar about an axis substantially parallel to the axis of rotation of said loop-taker shaft, means for actuating said pivotal support to impart rising and falling movements to said feed-dog, a feed-advance rocker disposed adjacent said feed-bar and having its rocking axis 20 substantially in a vertical plane containing the axis of rotation of said loop-taker shaft, means for actuating said feed-advance rocker, and connections with said feed-advance rocker for imparting work-advancing and return movements 25 to said feed-dog.

FRANK PARRY.
